FIG. 3

FIG. 2

FIG. 1

FIG. 4

FIG. 5

FIG. 7

FIG. 6

FIG. 1 is a perspective view of a matside wrestling scoreboard showing our new design, the side not shown being the same as the sides shown;

FIG. 2 is a side elevational view thereof;

FIG. 3 is a top plan view thereof; wherein the slope of the sides make the scoring indicia appear as wide U-shaped lines;

FIG. 4 is another embodiment of the design wherein the lowermost section only may be employed;

FIG. 5 is another embodiment wherein the two lower sections only may be employed;

FIG. 6 is another embodiment wherein the three lower sections only may be employed;

FIG. 7 is another embodiment wherein the lower four sections only may be employed.

The top of the embodiments of FIGS. 4, 5, 6, and 7 are of the same proportions as the top view shown in FIG. 3, but larger in size.

We claim:

The ornamental design for matside wrestling scoreboards, as shown and described.
